US0D1081571S

(12) **United States Design Patent** (10) **Patent No.:** **US D1,081,571 S**
(45) **Date of Patent:** **** Jul. 1, 2025**

(54) **JUMP STARTER WITH AIR COMPRESSOR**

(71) Applicant: **Shenzhen Xiaoshi Technology Co., Ltd.**, Shenzhen (CN)

(72) Inventor: **Qi Lu**, Shenyang (CN)

(73) Assignee: **Shenzhen Xiaoshi Technology Co., Ltd.**, Shenzhen (CN)

(**) Term: **15 Years**

(21) Appl. No.: **29/955,756**

(22) Filed: **Aug. 2, 2024**

(51) **LOC (15) Cl.** **13-02**

(52) **U.S. Cl.**

USPC **D13/107**
